Application February 25, 1939, Serial No. 258,534

9 Claims. (Cl. 212—8)

This invention consists in means for swinging pivotally mounted structures; and, while it is of general applicability, we have developed it in application to the swinging of the jib of a crane, 5 and in such application we shall particularly describe it. The swinging in vertical plane of the jib of a crane is technically called luffing. This luffing of the jib of a crane is commonly accomplished by means of pulley and cable. The 10 means of this invention involve the use of screw and nut. The objects in view are simplicity of structure and facility, speed, and accuracy of operation.

In the accompanying drawings Fig. I is a view 15 in side elevation of a gantry crane of turret type mounted to travel upon rails, in which the luffing means of our invention are employed; Fig. II is a view to larger scale and also in side elevation, showing fragmentarily the crane, and 20 showing in greater detail the luffing mechanism; Fig. III is a fragmentary view, showing the luffing mechanism in plan; Figs. IV and V are views in cross-section, showing the luffing mechanism to still larger scale on the planes respectively indicated at IV—IV and V—V, Fig. II; Figs. VI and VII are views in axial section and in end elevation of a certain nut and bearing assembly, and Fig. VIII is a view partly in side elevation and partly in axial section of such assembly; Fig. IX is a fragmentary view, showing in axial section, on larger scale than Figs. VI to VIII, the internally threaded portions of the nut and bearing assembly; and Fig. X is a diagrammatic view in side elevation of a draw-bridge 25 which includes a pivotally mounted element, and to which application is made of the swinging means of the invention.

The gantry crane of Figs. I—VIII affords example of the practice of the invention; the 30 invention is in no sense limited to this or any other particular form or type of crane; and, as is manifest on consideration of Fig. X, it is of general applicability in the swinging of pivotally mounted structures.

The crane stands upon a base 1 (in this instance a platform mounted to rotate turret-like upon a derrick 2). It includes a jib 3 pivoted to the base at 4 and adapted to swing in vertical plane upon such pivotal mounting. Such swinging in vertical plane is, as has been said, termed luffing. From a drum 5 rotatably mounted in base 1 a hoist line 6 extends throughout the length of the jib and supports in a suitably formed bight a block 7. Upon this block the 35 load is hung. It does not concern us further

to describe details and refinements of load carrying.

The jib 3 of the crane will be seen to be a truss structure, of general triangular outline, pivoted by one corner of the triangle upon the 5 base 1, and itself including a basal chord member 8. This chord member 8 of the arm is pivotally connected at one end to the base 1. A third member, a screw 9, is through intermediate parts presently to be described, pivoted at one 10 of its ends to the distal end of the pivotally mounted member 8 (at point 10) and at its other end (through intermediate parts) to base 1 at a point 11, remote from pivot 4. The base 1, the chord member 8, and the screw 9 thus form a 15 triangle (called in the industry an A frame). Of this triangle of members, the effective length of one (the screw 9) is variable; and by variation in the effective length of this member the frame is swung and luffing is effected. 20

The screw 9 is oppositely threaded at its two ends and carries upon its oppositely threaded ends two oppositely threaded nuts, 12 and 13. The nuts are pivotally mounted in pairs of links 14, 14 and 15, 15 that move in a runway 25 in a frame 16, and in their mounting are secured against rotation. These links are pivoted, one pair to arm 3 at 10, the other pair to base 1 at 11. It is manifest, then, that as screw 9 is rotated in one direction or the other and the 30 pairs of links drawn together or spread apart, the effective length of the screw as a member of the A frame is diminished or increased, and the arm 3 is swung upward or downward. The positions illustrated in full lines and in broken 35 lines in Fig. I indicate the shifting of position of the parts. The range of swing is not limited to the positions shown, but is of much wider extent.

The screw 9 may be equipped with a gear- 40 wheel 17, and the frame 16 with a motor 18, by which through suitable transmission mechanism rotation in desired direction, at proper speed, and to desired extent may be imparted powerfully to screw 9. 45

The frame 16 is assembled with the links 14, 14, 15, 15, and affords a "floating" runway and torsion-resisting member for the links and a support for the motor 18. Structurally the frame includes two parallel beams 160, spaced apart 50 and rigidly integrated with cross-struts 161. The screw 9 extends between the beams 160, and at opposite ends is journaled in bearing blocks 90 that are secured against axial displacement, by means of keepers 162 rigid with the frame. 55

The inner faces of the beams 160 carry longitudinal rails 26, upon which the links 14, 14 and 15, 15, when assembled with the nuts, are adapted to travel. The structure holds the links (and 5 the cups 23 presently to be described) against rotation. The links include lateral projections 141, 151 that are notched to engage the rails 26, as shown in Fig. IV; and between the paired links the nuts 12 and 13 are severally mounted.

10 Provision is made for the distribution of stress between nut and screw. The practical limitations upon the degree of perfection attainable in the preparation of materials and in the fabrication of parts give value to this provision.

15 The nut has gimbal mounting in the pairs of links; and, accordingly, under stress transmitted between screw and link, the nut adjusts itself upon the screw, and stress that might otherwise be concentrated at one point is distributed around 20 the circumference of the interengaged threads.

The gimbal mounting is found in a cylindrical cup 23 with a bottom orifice through which in the assembly the screw 9 extends, and within which the nut is arranged. Externally the cup is provided 25 with trunions 24 by which it is pivotally mounted in the associated pair of links (14, 14 or 15, 15). Internally the cup is provided with transversely extending cylindrical bosses, conveniently formed as pins 25 welded in orifices in

30 the cup walls. The axes of trunions 24 and of pins 25 are angularly displaced at a 90° angle, with respect to the axis of the shaft 9 as centre. Upon the bosses 25 the nut 21 makes thrust bearing, the bearing surface of the nut being cor-

35 respondingly cylindrical in shape. Elsewhere than over the thrust surfaces specified the nut has clearance, indicated at 28, from the surfaces of the cup.

The nut is compound, and includes the concentrically arranged parts 20 and 21. The inner part 20 is the threaded part; the outer part 21 engages the inner over the thrust surface of the transverse step 27, and it is the outer part that is immediately provided with the bearing surfaces 45 to engage the pins 25. The two parts are united against relative rotation by the spline 22.

Upon the part 21 a supplementary nut 30 is mounted by bolts 31, and by such mounting is minutely adjustable in its position. The supplementary nut 30 is provided upon its outer face (the face that in the assembly is remote from the nut 20, 21) with an outstanding diametrically extending ridge 32 of a width less than the overall diameter of the screw 9. The threads within 55 the nut 20 are so proportioned as to fill the complementary threads in the screw 9; the threads in the supplementary nut 30 are so proportioned as to afford a small play between the opposed surfaces of the threads. When the parts are initially assembled, the faces of the threads in nut 30, which otherwise would bear the stress of service, stand away from the thread on the screw 9. In consequence, it is the nut 20 that primarily bears the stress of service. As in continued use the 60 interengaging surfaces wear away, the space narrows at which the thread surfaces of the supplementary nut 30 stand apart from those of the screw. The narrowing of this space is visible as through a window at the sides of the ridge 32; 65 and thus a tell-tale is provided, by which determination may be made, when the nut 20 is so far worn as to require replacement.

Manifestly, it is only the reach of the screw 9 between the nuts 12 and 13 that is subject to the 70 tension stresses of the load, and, of course, if the

screw breaks, it will break at some point in the interval between the nuts. In the event of such screw failure, the two ends of the screw severally extending between the nuts 12 and 13 and the thrust blocks 90 at the opposite ends of the frame 5 16, become compression members, and transfer through the keepers 162 to the body of the frame 16 the load-sustaining tension, normally borne by the portion of the screw between the nuts. Thus, the frame 16, normally serving as a runway and 10 motor support, is adapted in emergency to become the effective load-sustaining member, preventing undue harm to the apparatus, and serious danger to workmen.

The nuts 20 will normally be formed of bronze; 15 but the supplementary nuts 30, serving their described purposes, not of tell-tale merely, but, if for any reason the threads in the bronze nuts 20 fail, of compression members also, will advantageously be formed of steel of high shear 20 strength.

The screw is supported in the frame by the nuts, and at the ends there is sufficient normal clearance from blocks 90 to allow for wear between screw and nuts.

The structure allows the screw to "float" in the nut assemblies 12 and 13, and, as has been said, the stress is distributed over the engaging surfaces around the circumference of the screw.

Already we have said that the screw 9 "floats" 30 in the frame 16, in that it is mounted in blocks that have universal pivotal mounting in the frame. Furthermore, it will be observed that the frame 16 "floats", in the sense that, in addition to its pivotal movement upon points 10 and 11, it has 35 movement of longitudinal translation relatively to base 1 and arm 3. Such movement is indicated in the broken-line position, Fig. I.

The operation of luffing is effected by rotation of screw 9 with the effect that the pairs of links 40 40 14, 14 and 15, 15 are drawn together or spread apart; the effective length of one arm of the A-frame is diminished or increased; and arm 3 is raised or lowered. In case the screw 9 breaks under load, the frame 16, through the keepers 45 162, becomes the tension member, sustaining the load.

In Fig. X a draw-bridge is diagrammatically shown, consisting of two halves 40 severally mounted pivotally upon opposed bridge-heads 50, and adapted to be swung severally from full-line to dotted-line positions. In this case also each bridge half is in structure a truss that includes a chord member 80. Between the distal end of chord 80 (the end remote from the point of pivoting) and a pivot 60 mounted on the bridge-head 50 at an interval from the pivotal point 70 of the chord member 80, such a structure as that already shown and described may be introduced. And, by means of such a structure, the 55 draw-bridge halves may be raised and lowered.

Whereas the bridge illustrated consists in two pivotally mounted bridge sections that are adapted to be swung severally between horizontal and elevated positions, the art is familiar with draw-bridges that have a single member that is adapted to be swung in vertical plane. Manifestly, the structure of the invention may be also employed in bridges of this sort.

In like manner, as will be understood, the invention may be applied to the swinging of the gates of locks in canals; and, generally, in the swinging of pivotally mounted structures.

We claim as our invention:

1. Means for swinging a structure pivotally 75

5 mounted upon a support, such means including a frame, two carriages mounted in the frame for longitudinal movement relative thereto, and pivoted severally to the structure and the support at points remote from the pivot point, two nuts 5 mounted on gimbal mountings, each in one of said carriages, and a screw simultaneously engaged by the two said nuts and adapted on rotation to effect the drawing together of the nuts 10 and of the carriages that bear them.

10 2. The structure of claim 1, the gimbal mountings including each a cup being pivotally mounted in one of said carriages on an axis transverse to the axis of the screw and each cup being additionally adapted to be pivotally engaged by the nut on an axis of turning also transverse to the screw axis and angularly displaced (with respect to the screw axis as a centre), from the axis of pivotal mounting first named.

15 20 3. In a crane structure including an arm in the form of a truss with basal chord member, pivotally mounted at one end of such basal chord member to an extended base, luffing means, including a frame with longitudinally extending runway, two oppositely threaded nuts mounted in said runway, one of said nuts being pivotally connected to the basal chord member of said arm at a point remote from the point of pivoting to the said extended base, and the other 25 of said nuts being pivoted to the said extended base at a point remote from the said point of pivoting of the arm upon it, and a rotatable bolt formed with oppositely threaded portions simultaneously engaging the two said nuts.

30 35 4. In a crane including an arm pivotally mounted upon a base, luffing means, including a frame with longitudinally extending runway, two links adapted to travel in said runway, two nuts mounted with universal pivotal connection, one to each link, a screw extending longitudinally of said frame and engaging the nuts in said links, one of said links being pivotally connected to said arm at a point remote from the point of pivotal mounting upon the base, and the other of said 40 carriages being pivotally connected to said base at a point remote from the point of pivotal mounting of the arm upon it.

45 5. In a crane including an arm pivotally mounted upon a base, luffing means, including a frame with a longitudinally extending runway, two links adapted to travel in said runway, two nuts mounted with universal pivotal connection, one to each link, a screw extending longitudinally of said frame and engaging the nuts in said links,

one of said links being pivotally connected to said arm at a point remote from the point of pivotal mounting upon the base, and the other of said links being pivotally connected to said base at a point remote from the point of pivotal mounting of the arm upon it, and means for rotating said shaft to vary the space interval between said links.

6. In a crane including an arm pivotally mounted upon a base, luffing means, including a screw 10 carrying two nuts connected, one to said arm at a point remote from the point of pivotal mounting upon the base, and the other to the base at a point remote from the point of pivotal mounting of the arm upon it, and a floating 15 frame borne by and providing runway for said nuts.

7. In a crane including an arm mounted upon a base, luffing means, including a frame with a longitudinally extending runway, two nuts adapted to travel in said runway, a screw extending longitudinally of said frame and engaging the said nuts, one of said nuts being pivotally connected to the said arm at a point remote from the point of pivotal mounting upon the base, 20 and the other of said nuts being pivotally connected to said base at a point remote to the pivotal mounting of the arm upon it, the said frame being provided with abutments beyond the two ends of said screw in such assembly, 25 whereby, in case of screw failure, the frame becomes a tension member sustaining the load.

8. In a crane including an arm pivotally mounted upon a base, means including a screw and a traveling nut for swinging said arm in vertical plane, and a frame including a runway for said traveling nut, said frame carrying an abutment adapted, in case of screw failure, to be engaged by said screw and to transmit the load stress to said frame.

9. Means for swinging a structure pivotally mounted upon a support, such means including a frame, two nuts rotatably borne by said frame and pivotally connected, one to the swinging structure and the other to the support, a screw 45 simultaneously engaged by the two said nuts and adapted on rotation in one direction or the other to effect the drawing together or the recession of the nuts from one another, a prime mover borne by said frame, and rotation-imparting connection between said prime mover and said screw 50
